(57) **CLAIM**

We claim the ornamental design for an integrally-formed closure for a container, as shown and described.

DESCRIPTION

FIG. 1 is a perspective view of the integrally-formed closure for a container in an open position.

FIG. 2 is a top view of the integrally-formed closure for a container in an open position.

FIG. 3 is a side elevation view of the integrally-formed closure for a container in an open position; and,

FIG. 4 is a side elevation view of the integrally-formed closure for a container of FIG. 3 in a closed position.

The broken line disclosure is for illustrative purposes only and forms no part of the claimed design.
